(73) Assignee: **Bethrick, Inc.**, Slinger, WI (US)

Non-Final Office Action dated Jul. 13, 2015 for U.S. Appl. No. 14/324,637 10 pages.

(**) Term: **14 Years**

(Continued)

(21) Appl. No.: **29/485,016**

Primary Examiner — Wan Laymon

(22) Filed: **Mar. 14, 2014**

Assistant Examiner — Mark Booker

(74) Attorney, Agent, or Firm — Foley & Lardner LLP

(57) **CLAIM**

I claim the ornamental design for a food and beverage plate, as shown and described.

DESCRIPTION

- (63) Continuation-in-part of application No. 29/468,184, filed on Sep. 26, 2013, now Pat. No. Des. 704,512.
(51) **LOC (10) Cl.** **07-01**
(52) **U.S. Cl.**
USPC **D7/557; D7/553.8**
(58) **Field of Classification Search**
USPC D7/557, 213, 550.1, 553.1–553.6,
D7/553.7–553.8, 549, 554.2, 396.1;
D9/499, 739, 759; 206/557, 562–564,
206/784, 814; 220/557, 561; 426/132, 143
CPC A47G 19/065; A47G 19/00; A47G 19/02;
B65D 1/36; B65D 81/00
See application file for complete search history.

FIG. 1 is a front perspective view from above of the claimed design including a beverage container as unclaimed background, according to one embodiment;

FIG. 2 is a front perspective view of the claimed design of FIG. 1;

FIG. 3 is a bottom perspective view of the claimed design of FIG. 1;

FIG. 4 is a top view of the claimed design of FIG. 1;

FIG. 5 is a bottom view of the claimed design of FIG. 1;

FIG. 6 is a front view of the claimed design of FIG. 1, wherein the left, right, and rear views are identical to the front view; and,

FIG. 7 is a section view of the claimed design along line 7-7 of FIG. 5.

The broken lines shown in the figures represent portions of the article that form no part of the claimed design. Broken lines formed by equal length dashes show unclaimed portions of the design. Broken lines formed of unequal length dashes (i.e., dash-dot) show boundaries between claimed and unclaimed portions of the design.
